US0D1040185S

(12) **United States Design Patent** (10) **Patent No.:** **US D1,040,185 S**
(45) **Date of Patent:** **** Aug. 27, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Michael C. Evashevski**, San Francisco, CA (US); **Monika E. Gromek**, Oakland, CA (US); **Joseph Andrew Magnani**, San Francisco, CA (US)

(73) Assignee: **Apple Inc.**, Cupertino, CA (US)

(*) Notice: Patent file contains an affidavit/declaration under 37 CFR 1.130(b).

(**) Term: **15 Years**

(21) Appl. No.: **29/807,175**

(22) Filed: **Sep. 9, 2021**

Related U.S. Application Data

(63) Continuation of application No. 29/728,764, filed on Mar. 20, 2020, now Pat. No. Des. 933,098.

(57) **CLAIM**

The ornamental design for a display screen or portion thereof with graphical user interface, as shown and described.

DESCRIPTION

The sole FIGURE is a front view of a display screen or portion thereof with graphical user interface showing the claimed design.

The peripheral dashed broken lines depict a display screen or portion thereof, and form no part of the claimed design. The broken lines within the peripheral dashed broken lines illustrate portions of the graphical user interface which form no part of the claimed design.

1 Claim, 1 Drawing Sheet
